(57) **CLAIM**

The ornamental design for a low dam outswing sill cap, as shown and described.

DESCRIPTION

FIG. 1 is a front upper perspective view of a low dam outswing sill cap according to a first embodiment of the disclosure;

FIG. 2 is a front lower perspective view thereof;

FIG. 3 is a top view thereof;

FIG. 4 is a right side view thereof;

FIG. 5 is a left side view thereof;

FIG. 6 is a bottom view thereof;

FIG. 7 is a front end view thereof;

FIG. 8 is a rear end view thereof from an end opposite that of FIG. 7;

FIG. 9 is a front upper perspective view of a low dam outswing sill cap according to a second embodiment of the disclosure;

FIG. 10 is a front lower perspective view thereof;

FIG. 11 is a top view thereof;

FIG. 12 is a right side view thereof;

FIG. 13 is a left side view thereof;

FIG. 14 is a bottom view thereof;

FIG. 15 is a front end view thereof; and,

FIG. 16 is a rear end view thereof from an end opposite that of FIG. 15.

The broken lines are for the purpose of illustrating environment only and form no part of the claimed design.

1 Claim, 10 Drawing Sheets
